UNITED STATES PATENT OFFICE.

HENRY GOOLD-ADAMS AND JOHN MITCHELL, OF LONDON, ENGLAND.

COUPLER FOR RAILWAY AND OTHER VEHICLES.

Application filed March 10, 1921. Serial No. 451,180.

To all whom it may concern:

Be it known that we, HENRY GOOLD-ADAMS and JOHN MITCHELL, both subjects of the King of Great Britain, residing in London, England, have jointly invented certain new and useful Improvements Relating to Couplers for Railway and Other Vehicles, of which the following is a specification.

- 10 The invention relates to coupling devices for railway and other vehicles and more particularly to means for automatically ensuring a tight coupling under all conditions of wear between vehicles in which the connection is effected by the Norwegian hook type of coupling.

It is well known that in such method of connection although the coupling devices may be tight when the parts are new, the wear unavoidably occurring at the heads, the pin on which the hook is pivoted and the surfaces by which the hook and block engage cause in time an amount of slackness which is detrimental and may affect the reliability of the system. For this reason it has been proposed to provide a linked system connected to a right and left handed screw and pivoted to a longitudinally sliding block, by which any play in the working parts can be manually taken up after the vehicles are coupled.

According to the invention, the required tight coupling between the engaged parts is maintained automatically by spring pressure acting on a wedge shaped member, which in one form of the invention is applied to and forms part of the bar engaging the hook either directly or through an intermediate member and in an alternative construction forms the pin on which the hook is pivoted. In either arrangement any looseness or play due to wear of the working parts is automatically taken up by the constantly acting spring pressure.

45 In the simplest form of the construction according to the invention a single centrally disposed spring is provided tending to draw inwards the wedge shaped surface of the locking bar.

50 The application of pressure opposing the spring withdraws the wedge shaped member and allows the hook to be lifted for uncoupling the vehicles.

A suitable device, which may be for instance a gravity latch or a pawl engaging in teeth cut in the locking bar, holds the

latter in the uncoupling position and is released when the coupling is to be effected.

Instead of the single central spring a spring may be provided on one side of the 60 coupler head, or a pair of springs may be disposed respectively on either side of the coupler head and the locking bar may be formed with two wedge shaped surfaces tapering from the centre outwards. This 65 arrangement allows the locking bar to be drawn outwards from either side of the coupler head.

In the accompanying drawings which represent examples of constructions according 70 to the invention, Fig. 1 is an elevation and Fig. 2 a plan of a Norwegian hook coupling in which a wedge shaped locking bar engages with the hook and the spring is disposed on one side of the coupler head. Fig. 75 3 shows a pawl and ratchet for holding the locking bar in the position for uncoupling. Fig. 4 shows in end elevation a locking bar with central spring. Figs. 5 and 6 show, respectively, in elevation and plan a coupling device in which the locking bar is applied to the rear end of the hook. Figs. 80 7 and 8 show, respectively, in elevation and plan a locking bar engaging a coupling block. Fig. 9 shows in end view the locking bar and central spring. Figs. 10 and 11 show, respectively, in elevation and plan a modification in which the locking bar engages one arm of a two armed pivoted lever, the other arm of which engages with the 90 hooked end of the Norwegian hook. Fig. 12 shows a vertically arranged locking bar. Fig. 13 is a plan of a locking bar with double wedge surfaces and is adapted to be pulled out from either side of the coupler 95 head.

In the arrangement shown in Figs. 1 to 4, A and B are two coupler heads, C a Norwegian hook, c its pivot pin, c' the part of the hook engaging the locking bar D, d 100 an inclined and d' a straight side of the bar forming a wedge shaped surface passing through suitably formed recesses b' and b'' in the side walls of the coupler head B. One end of a spring E abuts against a side wall of the coupler head B, the other end of the spring is held in a cap e secured to a rod d' 105 integral with the locking bar D.

The spring is under compression and tends always to draw the locking bar inwards and thereby to force the part c' of the hook C and with it the pivot pin c and

coupler head A towards the right, ensuring contact between the coupler heads and automatically taking up any slackness or wear in the working parts.

- 5 In order to allow the heads to be uncoupled, the locking bar is pulled outwards by a handle d^3 against the action of the spring E, whereupon the hook can be lifted to uncouple the vehicles.
- 10 The locking bar can be held in the uncoupled position by any suitable device, for example by a combined latch and handle F engaging in known manner in a recess d^4 provided in the locking bar. The latch and 15 handle are preferably formed as a bell crank lever, one arm f of which engages in the recess d^4 , the other arm f' of the lever serving as a handle and by its weight forcing the latch automatically into locking engagement with the bar. The lever turns on a pin f^2 , which, in the example shown, is extended through the side walls of the coupler head in order that a second handle F' can be fitted on the opposite side to the latch 20 and handle F, so that the release of the locking bar can be effected from either side by simply raising the corresponding handle.

Fig. 3 shows a pawl g and ratchet g' for retaining a locking bar D in the uncoupling 30 position. In this case it is only necessary to lift the pawl g to release the bar D. Obviously, a pawl and ratchet device can be applied in a similar manner to hold the locking bar securely in its indrawn position.

- 35 In Fig. 4 the spring E is arranged centrally below the locking bar D; one end of the spring abuts against the side wall b^2 of the coupler head and the other end of the spring abuts against a lug d^5 of the bar 40 D. The spring is supported by an axially disposed rod d^6 secured to the lugs d^5 and d^7 of the bar D.

In the construction shown in Figs. 5 and 45 6 the locking bar D forms the pivot pin of the hook C. The construction of the locking bar, spring and latch is otherwise similar to that shown in Figs. 1 and 2. The oval bearing hole c^2 provided in the hook C engages with the rounded surface of the wedge shaped locking bar. As the latter is drawn inwards by the spring E the hook C and with it the coupler head B is drawn to the left to take up any slackness in the working part.

- 55 In the example shown in Figs. 7-9 the hook C engages in the sliding block H actuated by the locking bar D' which is somewhat differently formed from the bar D of the previously described construction.

60 The spring E is shown as centrally arranged in a recess of the walls of the coupler B below the upper portion of the locking bar, an inclined rib d^8 of which engages in a correspondingly shaped recess h' in the 65 sliding block H. A latch d^9 may engage in

a recess d^{11} provided in the lower part d^{10} of the locking bar, or a pawl and ratchet device may, as previously described, hold the bar in the uncoupling position. Projections d^9 of the bar D' support the spring E. A key k prevents the locking bar from being pulled out from the coupler head.

As the wedge shaped bar D' is drawn inwards, the block H and with it the hook C and the coupler head A is drawn to the right to take up any play in the parts. When the locking bar is being withdrawn, the inclined rib d^8 engaging in the correspondingly shaped recess h' in the sliding block H carries the block towards the face of the coupler head, whereupon the hook can be lifted for uncoupling the vehicles.

The inclined rib d^8 also retains the sliding block H in a position ready for coupling after the locking bar has been withdrawn.

A strut b^0 integral with the coupler head B extends between the walls of the coupler head and sustains the load transmitted through the coupling block H to the locking bar D' and thereby obviates any bending of the locking bar D'.

In the modification shown in Figs. 10 and 11, L is a two armed lever pivoted at I; the wedge shaped extension d^7 of the locking bar D engages with the upper surface of the approximately horizontal arm l^1 of the lever L; the other arm l^2 of the lever L which is curved and substantially at right angles to the arm l^1 engages with the hooked end c' of the Norwegian hook C. The locking bar slides in the walls b^1 , b^2 of the coupler head B under the action of the spring E which in the example illustrated is centrally arranged with respect to the locking bar. As the locking bar is automatically drawn inwards by the spring E the lever L is rotated in the clockwise direction and draws the head A into contact with the head B.

In the construction shown in Fig. 12, the vertical locking bar D² engages in a sliding block H, which is similarly arranged to the block shown in Fig. 7 and engages in a similar manner with the Norwegian hook C.

In the modification shown in Fig. 13, the locking bar D² is formed with two wedge shaped surfaces d^{12} , d^{13} , and springs E' and E² are provided respectively on each side wall of the coupler head B. Two latches are also provided engaging in corresponding recesses of the locking bar. In other respects the construction is substantially similar to that shown in Figs. 1-4, but has the advantage that the locking bar can be withdrawn into the uncoupling position from either side of the coupler head. In the position shown the handle d^3 has been pulled so as to bring the part d^{12} of the locking bar into engagement with the part c' of the hook C. The spring E' is in compression and the spring 120

E² in tension, both forces tending to move the locking bar inwards. If the handle on the other side of the coupler head B had been pulled, the part d¹³ of the locking bar would have been in engagement with the hook C, spring E² would have been in compression and spring E' in tension and both forces would have tended to pull the bar inwards, viz: into the central position. Or one spring 10 may be under compression while the other spring is inoperative.

Having thus described the nature of the said invention and the best means we know of carrying the same into practical effect, 15 we claim:—

1. A coupling for railway or like vehicles, comprising a pair of complementary coupler heads for application, respectively, to the abutting ends of two adjacent vehicles, a 20 hook pivoted to one of said heads, a member on the other head, and means for maintaining said member automatically in contact with said hook comprising a wedge shaped locking bar in the other head movable transversely of the axis of the coupler heads and a spring for moving said wedge.

2. A coupling for railway or like vehicles, comprising a pair of complementary coupler heads for application, respectively, to the 30 abutting ends of two vehicles to be coupled together, a hook pivoted in one of said heads, a member in the other head with which said hook is adapted to engage, a spring actuated wedge-shaped locking bar slidably mounted 35 for movement in said other head adapted to actuate said member.

3. A coupling for uniting two railway or like vehicles comprising a coupler head for application to one vehicle having a hook 40 pivotally mounted thereon, a coupler for application to the adjacent end of the other ve-

hicle having a member movable longitudinally of said couplers and adapted to engage said hook, a wedge shaped locking bar in said second-named coupler engaging said 45 longitudinally movable member for moving the same, and a spring for actuating said locking bar.

4. A coupling for uniting two railway or like vehicles comprising a coupler head for 50 application to one vehicle having a hook pivoted thereto, a coupler head for application to the adjacent end of the other vehicle having a longitudinally slidable block adapted to engage said hook, said block having a 55 recess therein, a wedge shaped locking bar slidable transversely of said second-named coupler and having an inclined rib adapted to slidably engage in said recess, and a spring for actuating said bar at right angles 60 to the axis of said coupler heads.

5. A coupling for uniting two railway or like vehicles comprising a coupler head for application to one vehicle having a hook pivoted thereto, a coupler head for application to the adjacent end of the other vehicle having a longitudinally slidable block adapted 65 to engage said hook, said block having a recess therein, a wedge shaped locking bar slidable transversely of said second-named 70 coupler and having an inclined rib adapted to slidably engage in said recess, a spring for actuating said bar at right angles to the axis of said coupler heads, said locking bar having a recess therein, and a latch on the 75 coupler head adapted to engage in said recess.

In testimony whereof we have signed our names to this specification.

HENRY GOOLD-ADAMS.
JOHN MITCHELL.
